UNITED STATES PATENT OFFICE.

HENRY C. WELKER, OF MINNEAPOLIS, MINNESOTA, ASSIGNOR TO DEERE & COMPANY, OF MOLINE, ILLINOIS, A CORPORATION OF ILLINOIS.

PLOWBRACE.

Application filed March 23, 1920, Serial No. 368,059. Renewed September 11, 1922. Serial No. 587,565.

To all whom it may concern:

Be it known that I, HENRY C. WELKER, a citizen of the United States, residing at Minneapolis, in the county of Hennepin and State of Minnesota, have invented certain new and useful Improvements in Plow-braces, of which the following is a specification, reference being had therein to the accompanying drawing.

10 This invention relates to gang plows and has to do particularly with means for bracing the rearward portions of the beams that carry the soil working bodies.

15 In plows of the class to which this invention relates the several beams are joined together to form a rigid, substantial frame for carrying the plow bodies in their proper fixed relationship and it is an object of the invention to provide means for bracing the 20 rear portions of the beams so that when the plow strikes obstructions, such as stones, stumps or roots, the shocks and strains are more equally divided between the beams and their bracing members and the springing 25 of the beams and braces or shearing of the bolts or pins uniting the beam and braces is prevented.

30 In the accompanying drawing presenting an embodiment of the invention, a three beam plow is shown but I do not restrict myself to this number of beams and plow bodies for the invention is readily adaptable to a plow having a larger number of beams.

35 Figure 1 is the plan view of a gang provided with my bracing means.

Figure 2 is a sectional view on a line *a—a* of Figure 1, and

40 Figure 3 is a detail view showing a method of attaching the bracing means to an intermediate beam.

45 Referring to the drawings 5, 6 and 7 indicate plow beams carrying plow bodies 8, 9 and 10. The beams 5 and 6 are connected together at the front by means of braces 11 and 12, and are also connected near their central portion by means of a brace 13 and near their rearward portion by a brace 14. The beam 7 near its front portion is connected with the beam 6 by a laterally extending bracket like brace 15 and at its rearward portion is also connected with the beam 6 by a brace 16. It will thus be seen the beams 5, 6 and 7, are connected together by 55 the braces 11, 12, 13, 14, 15 and 16 to form

a rigid frame for carrying the plow bodies 8, 9 and 10.

It is usual to mount plows of this type on wheels, and 17 indicates the front furrow wheel mounted on a cranked axle 18 which 60 is secured to the plow frame by brackets 19 and 20 attached to the beams 5 and 6. 21 is a lever for adjusting the front furrow wheel 17 in a usual and well known way. 22 indicates the landwheel mounted on a cranked 65 axle 23 which is secured to the plow frame by brackets 24 and 25 attached to the brace 15 and the beam 5 respectively. The landwheel 22 can be adjusted by means of a lever 26 in the usual and well known way. 27 70 indicates the rear furrow wheel mounted on an axle 28 journaled in the vertically positioned sleeve 29, which is attached to the beam 7 by straps 30—30.

75 In plows of this type when any of the plow bodies strike an obstruction a severe strain is transmitted to the beams and bracing members and to more nearly equalize and properly distribute this strain a member 31 is provided. The member 31 is connected to the intermediate beam 6 by means of a bolt 32, a bracket 33 and a bolt 34. The end portions of the member 31 rest on the brace 14 and the brace 16 respectively and are formed in such a manner that in conjunction with the bolt 32 the member 31 is 80 prevented from moving bodily laterally of the braces 14 and 16. The end parts of this brace member, however, are not rigidly fastened to any of the parts, but are supported 85 loosely, and if sufficient stress is exerted by the bolt upon the central part a slight movement laterally of the end parts will be caused.

90 The member 31 is preferably formed of 95 metal U-shaped in cross section as shown in Figure 3. This form of brace readily lends itself to the purpose and at the same time is light, strong and economical of manufacture.

100 By making the member 31 in the form of an arch and connecting its arched portion with the beam 6 and having its end portions resting on the braces 14 and 16, the member 31 forms a supplemental vertically 105 acting brace which can be made of lighter material than if it were made straight.

110 By arching it provision is made for having an ample space above the planes of the

beams to permit such slight down-bending of the central part of the brace as occurs when the strain is exerted by the bolt 32.

It is apparent that by providing a brace 5 similar to that at 31 it can be caused to act in such way as to distribute the strains and stresses throughout the structure and hold the beams in desired relation to horizontal planes. In case any relative displacement 10 of the parts should occur after the plow has been in use, tightness can be restored and a continuing strain exerted by means of the bolt at 32.

What I claim is—

15 1. In a plow frame, the combination of a plurality of spaced beams connected together at the front, means connecting the rear portions of the beams, and a transversely positioned member connected with the rearward portion of an intermediate 20 beam and having its ends supported by the means connecting the rear portions of the beams.

25 2. In a plow frame, the combination of a plurality of spaced beams connected together at the front, means connecting the rear portion of the beams, and a transversely positioned member connected with the rearward portion of an intermediate 30 beam and having its ends connected with the rear portions of the side beams to resist movement of either of the side beams independently of the intermediate beam.

35 3. In a plow frame, the combination of a plurality of spaced beams connected together at the front, means connecting the rear portions of the beams, and a transversely positioned arched member connected in its arched portion to the rearward portion 40 of an intermediate beam, the ends of the arched member connected with the rear portions of the side beams to resist movement of either of the side beams independently 45 of the intermediate beam to which the arched member is connected.

4. In a plow frame, the combination of a plurality of spaced beams connected to-

gether at the front, means connecting the rear portions of the beams and a transversely positioned member connected with the rearward portion of an intermediate beam, the ends of the transverse member supported by the means connecting the rear portions of the said beams, the ends of the said transverse member forming means to prevent lateral movement of the transverse member in relation to the means connecting the rearward portions of the beams. 50 55

5. In a plow frame, the combination of a plurality of spaced beams connected together at the front, means connecting the rear portions of the beams, and a transversely positioned arched member connected with the rearward portion of an intermediate beam, the ends of the arched member supported by the means connecting the rear portions of said beams, the arched member forming a truss to prevent independent movement of the beams. 60 65

6. The combination of the plow frame 70 having side beams and an intermediate beam, and devices connecting the rear portions of said beams, of means supplemental to said connecting devices adapted to exert stress vertically in one direction, through laterally movable elements, upon the rear portions of the side beams and to exert stress vertically in the opposite direction upon the intermediate beam. 75

7. The combination with the plow frame 80 having a plurality of laterally spaced, approximately parallel beams joined together by connecting devices positioned on transverse lines, of devices to retain all of the beams in common horizontal planes comprising a transversely disposed member 85 having loosely held end elements normally movable laterally and adapted to exert downward stress through said end elements upon the beams, respectively, at the sides 90 of the central, vertical, longitudinal plane of the frame and to exert opposing upward stress upon the central part of the frame. 95

HENRY C. WELKER.
